(57) **CLAIM**

I claim the ornamental design for an electrical connector, as shown and described.

DESCRIPTION

FIG. 1 is a top plan view of an electrical connector of an embodiment showing my new design;

FIG. 2 is a front elevational view thereof;

FIG. 3 is a rear elevational view thereof;

FIG. 4 is a bottom plan view thereof;

FIG. 5 is a right side elevational view thereof;

FIG. 6 is a front, top, and right side perspective view thereof;

FIG. 7 is a front, bottom, and right side perspective view thereof;

FIG. 8 is a right side elevational view thereof, in an open state;

FIG. 9 is a front, top, and right side perspective view thereof, in an open state; and,

FIG. 10 is a front, top, and right side perspective view thereof, in a use condition coupled with a platy signal transmission media.

Herein, the left side elevational view is a mirror image of the right side elevational view. Also, the evenly spaced broken lines in the drawings illustrate features of the electrical connector and environmental subject matter that form no part of the claimed design. The dot-dash broken lines in the drawings illustrate borders between claimed and unclaimed subject matter and form no part of the claimed design.
